UNITED STATES PATENT OFFICE.

THEOPHILUS TREMBLE, OF BAY CITY, MICHIGAN.

CLOTHES-DRIER.

SPECIFICATION forming part of Letters Patent No. 353,332, dated November 30, 1886.

Application filed September 7, 1885. Serial No. 176,354. (No model.)

To all whom it may concern:

Be it known that I, THEOPHILUS TREMBLE, a citizen of the United States, residing at Bay City, in the county of Bay and State of Michigan, have invented a new and useful Improvement in Clothes-Driers, of which the following is a specification.

My invention relates to improvements in that class of clothes-driers in which a central standard is supported in a vertical position by extended legs, the said standard supporting outward-extended arms, upon which are placed the clothes for drying; and the objects of my invention are to provide a clothes-drier which may be cheaply and easily constructed and operated, and which can be compactly folded together, so that but a small amount of room is required for packing away or shipping the device, and at the same time make a strong and durable drier when the parts are extended to receive the clothes. I accomplish these objects by means of the device illustrated in the accompanying drawings, in which—

Figure 1 is an elevation, partly sectional, of my improved drier extended for receiving the clothes. Fig. 2 is the same folded for shipping. Figs. 3, 4, and 5 are views of the sleeve and supporting-piece detached. Fig. 6 is a top view of the base and foot.

Similar letters refer to similar parts throughout the several views.

a represents a vertical standard, firmly secured at its lower end to the base *b*, the outward extending ends of which are provided with a slot, *b'*, cut into the ends for a short distance, and into which is placed the outward extended foot-piece, *c*. These pieces *c* are provided with a longitudinal slot, *c'*, and a bolt, *d*, is passed through the base *b* and also through the slot *c'*, the slot *c'* and the bolt *d* being so arranged that the upper end of the piece *c* will rest, when the piece is extended, upon the solid portion of the base at the end of the slot *b'*, and bring the weight of the drier to bear upon the bolt *d*, as shown in Fig. 1, so that when the inner end of the piece *c* is raised up the bolt *d* will slide in the slot *c'*, and allow the piece to be brought to the position shown in Fig. 2, a notch, *d'*, being cut into the piece at the lower end of the slot *c'*, which, when the

pieces are brought to the position shown in Fig. 2, catches the bolt *d*, and prevents the piece from sliding out when the drier is lifted for removal.

At the upper end of the standard *a* is firmly fixed, by means of a pin passed through the piece *e* and standard *a*, or other suitable fastening, the circular piece *e*, which is arranged with its outer portion, *g'*, extending downward to a considerable distance, forming a circular hollow space beneath, and the upper and outer portion is provided with openings *e'*, the outer or lower end of the portions between the openings being joined by the part *f*, and the upper and inner end of the openings are closed by the part *f'*, which projects for a short distance from the standard *a*. Through these openings *e'* are projected the arms *g*, upon which the clothes are to be hung. The inner ends of the arms *g* are secured to a sleeve, *h*, which surrounds the standard *a*, and is provided on its upper edge with a projecting rim, *h'*, into which are formed the slots *i*, into which are placed the inner ends of the arms *g*, and the outer edge of the portion *h'* is provided with a groove, *i'*, into which rests the wire *n*, which also passes through the arms *g*, and serves to hold the arms in their position within the slots *i*, the outside circumference of the projecting part *h'* being of such dimensions as to allow it to pass within the downward extending part *g'* of the piece *e*, so that when the arms are extended in a horizontal position, as shown in Fig. 1, the inner end of the arm rests with its upper edge against and beneath the part *f'*, and with its lower edge, a short distance from its end, bearing upon the connecting part *f*, which serves to support the arms in an extended position, as shown in Fig. 1. When the arms *d* are raised to a vertical position, the sleeve is moved downward upon the standard *a*, and the arms slide within the openings *e'* to the position shown in Fig. 2.

A second set of arms and supports, similar to that described, may be placed upon the standard at a proper point below to allow suitable room for folding the parts, and the capacity of the clothes-drier will be doubled, and the entire apparatus may be folded so that a very small amount of space will be required for storing or shipping the same.

Having fully described my invention, what I claim as new, and desire to secure by Letters Patent, is—

In a clothes-drier, the standard *a*, having the supporting-piece *e* on its upper end and provided with the openings *e'*, the sleeve *h*, sliding upon the standard, the arms *g*, pivoted to the sleeve and passed through the openings *e'*, and the base *b*, firmly secured to the stand-

ard and provided with the slots *b'*, in combination with the foot-piece *c*, resting in the said slots *b* and provided with the slots *c'*, and the bolt *d*, passing through the base and slot *c'*, substantially as and for the purpose set forth.

THEOPHILUS TREMBLE.
